UNITED STATES PATENT OFFICE.

HALBERT K. HITCHCOCK, OF TARENTUM, PENNSYLVANIA.

METHOD OF APPLYING ABRASIVES TO GRINDING-MACHINES.

1,089,705.

Specification of Letters Patent. Patented Mar. 10, 1914.

Original application filed July 31, 1911, Serial No. 641,484. Divided and this application filed May 17, 1912. Serial No. 697,864.

To all whom it may concern:

Be it known that I, HALBERT K. HITCHCOCK, a resident of Tarentum, in the county of Allegheny and State of Pennsylvania, have invented a new and useful Improvement in Methods of Applying Abrasives to Grinding-Machines, of which the following is a specification.

This invention relates to a method of handling, grading and applying finely divided material mixed with liquid, such as sand or other abrading material for use with grinding machines.

In the grinding and smoothing of material requiring a smooth surface, such as plate glass, marble and granite, it is desirable that after the abrasives have passed between the material to be ground and the runners or rubbing bed, the finer particles be separated from the coarser ones and saved to be used in the finishing operation and the coarser particles returned to the grinder to assist in the roughing operations.

The object of the present invention is to provide a method of grading and applying such materials wherein the supply to and withdrawal of the material from the grading vessel goes on simultaneously, the finer material during the roughing operation being held back for the subsequent smoothing and finishing operation.

Further objects of the invention are to provide a method whereby the proper ratio of the water or other liquid to the sand or other abrading material may be regulated; to provide a method which requires simpler and less expensive apparatus than with the methods heretofore suggested; and to provide for starting the finishing operation at any time and bringing it to a speedy close by a series of steps or jumps from a coarse to a fine grade, as will be fully described hereinafter.

In the accompanying drawings, Figure 1 is a vertical sectional view of apparatus for carrying out the method; Fig. 2 is a vertical view through the discharge mechanism from the primary grading cone; Fig. 3 is a plan view of the same; Fig. 4 is a transverse vertical section on the line 4—4, Fig. 2; Figs. 5 and 6 are detail views showing different positions of the valve; Fig. 7 is an enlarged vertical sectional view of the valve controlling the outlet from the fine sand cone; and

Fig. 8 is a horizontal section on the line 55 8—8, Fig. 7.

In my Patent No. 934,441 issued September 21, 1909, is described and claimed a certain process for grading fine material in suspension, and in my Patent No. 934,612, September 21, 1909, I have illustrated and described certain apparatus for grading material, conducting the same to a grinding apparatus and then returning it for regrading.

The method of grading or separating the material into grades of the present application has certain general resemblances and follows the same broad principle as the method described in my Patent No. 934,441 above identified.

In the use of the apparatus illustrated in Patent No. 934,612, part of the material after being graded is deposited in tanks or bins from which it is taken to the grinding machines as necessary or desired, and upon the return from the grinding machines is regraded and again deposited in such tanks or bins. The material is not continuously in suspension in the liquid in which the grading is affected, nor is there a continuous cycle of circulation, that is, a withdrawal of material from the grading apparatus simultaneously with its introduction thereto, but rather an interrupted or intermittent cycle. Consequently, a comparatively large and expensive apparatus was required.

The present invention has for its purpose to provide a method for which simpler and less expensive apparatus can be employed and in which a continuous uninterrupted cycle with the abrading material in suspension is carried on so that the material can be handled at less cost and with less labor than with the apparatus shown in my prior patent.

In the drawings I have illustrated apparatus and herein will describe the mode for grading abrading material and applying the same for glass grinding operations, but it will be understood that certain features of the invention are applicable to grading materials and applying them to other purposes.

In the drawings 1 indicates a grinding table provided with a pair of runners 2 of the usual form. This grinding mechanism may be of any kind or type and as shown is

a conventional type largely used for grinding plate glass. Such tables are so well understood that specific description of the table illustrated is unnecessary. The table 5 is surrounded by a gutter 3 connecting with a cross gutter or conduit 4 which conveys the water and used abrading material over a screen 5 to a pit or sump 6, from which it is drawn through pipe 7 by means of a centrifugal pump 8 driven by any suitable motor and forced through pipe 9 into the bottom of the grading vessel 10. The grading vessel is arranged to regrade the used, and grade the new, materials so as to retain all 10 of the material coarser than a given size. The centrifugal pump 8 forces the mixture of sand and water upwardly through the vessel 10, so that the upflowing stream therein causes the material to grade itself 15 according to size upon the principle explained in my Patent No. 934,441, above referred to. The dirt, scummy material and abrasive material which is too fine for further use escapes through the overflow pipe 20 25 11 to a suitable conduit or sewer 12, which also carries the overflow from the sump 6. The finest grade of sand in the grading vessel 10 escapes through an outlet 13 near the top of said vessel to the fine sand cone 14 30 which is arranged in proximity to the main grader and at such a level that the fine sand mixed with water flows thereto by gravity. The fine sand collected in the cone 14 is used 35 for the final or finishing grinding of the glass, after the rough grinding has been effected by the coarser material drawn from the grading vessel 10.

The fresh abrading material or sand can be added to the system at any point, either 40 into the grading vessel 10, or directly upon the table, or in the gutter surrounding the latter. In the drawing 16 represents a clam shell bucket and 17 a conduit, either of which may be used for supplying fresh sand 45 to the system, such as by depositing the same in a hopper or bin 18 from which it is admitted as necessary into the vessel 10, in order to replenish the supply of sand due to the loss of a portion which becomes pul- 50 verized in the grinding operation and is washed out through the overflow 11. Any other manner of supplying fresh sand to the system will serve my purpose equally as well.

55 The grading vessel 10 may be of any size or form, but preferably is of inverted cone shape, as shown, with the side walls having such slope and the vessel having such diameter that the several grades seek a state 60 of equilibrium therein at well defined strata and at the points from which they are to be withdrawn, depending upon the ratio of the weight of the particles to the resistance offered to falling in the upward current of 65 water, as described in my Patent No.

934,441, above identified. The action of the upward flow of water in this conical vessel separates the material into grades, the coarsest being at the bottom and the successive strata decreasing in coarseness toward the top. In order to separately withdraw the grades from the grading vessel there are projected into said vessel a series of pipes 21, 22 and 23, in number depending upon the grades which are to be separately withdrawn. The lower or inner ends of these pipes are at different heights in the grading vessel and each opens approximately in the strata or zone of the grade which it is desired to withdraw through that pipe. These open ends are preferably arranged close to the center of the cone and all of the pipes extend through the side of the cone at substantially the same level. The outer ends of these pipes are bent downwardly somewhat, as shown, and they are arranged to discharge into spout 25 which projects over the grinding table, preferably between the runners, and which is perforated to discharge the mixture of sand and water onto the table. 70 75 80 85 90

The discharge ends of the pipes 21, 22 and 23 are controlled by independent valves, these valves being numbered respectively 27, 28 and 29, and are shown mounted upon a common axis but so as to be independently operable. The valve 27 is secured to a tubular shaft 30 provided with operating sheave 31; the valve 28 is connected to shaft 32 which extends through the hollow shaft 30 and is in turn provided with operating sheave 33; and the valve 29 is secured to shaft 34 provided with operating sheave 35. Each of these operating sheaves is weighted, as at 36, so that when closed the weight holds the valves closed against the head or pressure of mixture in the grading vessel, and when opened this weight keeps the valve open. Each sheave is provided with a rope or similar device 37 for operating the same. Each of the valves is provided with a soft packing or face 38 arranged to seat against the open end of the pipe and close the same. When the valves are open the mixture of sand and water is forced out of the pipes, 105 by the pressure of the head in the cone 10, but this pressure is not so great but that when the valves close the pipes, the outflow immediately ceases, but as soon as a valve is opened a flow through the open pipe is set 110 up. As soon as a valve is closed the sand in the pipe drops out of the same into the cone 10 due to the fact that there is no upward flow of water in the pipe, so that the sand gradually drops down until it escapes 120 from the inner open end of the pipe. Consequently the pipes ordinarily do not clog but are filled with practically clear water during such time as the mixture is not being withdrawn from the same. In case sand or 125 130

anything else should clog in any of these pipes from any cause I have provided the following arrangement for clearing the same: The outer ends of the pipes are connected to a suitable chamber 40 which is supplied with water under pressure through pipe 41. From chamber 40 a port leads to the outer end of each of the withdrawal pipes. Each of these ports is controlled by a check valve 42 held by spring 43 to normally close communication from the chamber to the end of the discharge pipe. To unseat any one of the valves 42 and open communication from chamber 40 to the desired one of the withdrawal pipes, the valves 27, 28 and 29 are each provided with a projection or prong 44 of sufficient length to contact with its respective check valve 42 and lift the latter from its seat whenever the rubber facing or packing 38 is compressed. In the normal condition of the closed valve (Fig. 2) the projection or prong 44 barely contacts with the valve 42 but does not lift the same from its seat. Should, for any cause, one of the withdrawal pipes become clogged the rope 37 for the valve of that particular pipe is pulled upon in a direction to forcibly compress the packing 38, which permits the prong 44 to lift the corresponding valve 42 from its seat (Fig. 5). Water under pressure from the supply pipe 41 now flows inwardly and downwardly through the clogged pipe and clears the same of the obstruction.

Inasmuch as each of the valves 27, 28 and 29 is independently controlled this permits of the withdrawal of the several grades separately and independently and to any extent or degree. In other words, it is not necessary to withdraw all of the grades lying between any two planes before taking out or beginning to take out an upper or finer grade. This enables the finishing operation to be brought to a speedy conclusion, whereas with prior apparatus where the different grades were withdrawn through a common outlet, it was necessary to entirely withdraw all of the grades before the finest could be taken out. With the new arrangement the withdrawal through any one pipe can be stopped whenever desired and any one of the higher pipes opened. This enables the material to be withdrawn in a series of steps or jumps and enables the finishing operation to be started at any time and to be brought to a speedy conclusion.

The grading of the material in the vessel 10 goes on simultaneously with the discharge of the graded material therefrom, the supply of ungraded material being continuously forced upwardly from the bottom of said vessel from the sump 6, as it comes from the grinding table.

In the application of abrading material,

and particularly for grinding and smoothing plate glass, it is advantageous to vary the amount of water mixed with the sand of the different grades. With the coarser grades a small ratio of water can profitably be used, while with the finer grades the ratio of water preferably should increase. In the apparatus illustrated the regulation of the ratio of water and sand for the different grades is automatically effected by properly proportioning the shape or slope of the cone 10 and properly locating the points of withdrawal of the different grades therefrom, that is to say, the different heights at which the withdrawal pipes terminate in said cone. By properly designing the shape of the cone and having the several withdrawal pipes projecting down into the cone to exactly the right points, the ratio of water to the sand is so regulated as to secure an increasing ratio of water to the sand for the finer grades.

The fine sand cone 14, as heretofore pointed out, receives its supply from the top stratum of the grading vessel 10. The sand from this fine sand cone is withdrawn only at the end of the grinding operation, to effect the finer or finishing grinding operation. The fine sand in cone 14 is also preferably graded therein by an upward current of water which is introduced into the bottom of the cone, such as through pipe 47 which projects down centrally in said cone and which is open at its lower end. This pipe has a supply connection 48. The surplus water escapes through the overflow 49 and preferably goes to the gutter 3. The effect of this is to further grade the fine sand in the cone 14, bringing the coarser sand at the bottom and gradually increasing in fineness toward the top so that when withdrawn through the bottom discharge orifice 50 to the spout 25 the finishing sand gradually becomes finer and finer. The discharge orifice 50 of the fine sand cone is controlled by a valve 51 secured to a stem 52 guided in the lower end of tube 47, said stem being fluted or grooved, as at 53, so that it can not stop the flow of water from the pipe 47. Connected to the valve stem 52 is a rod 54 extending upwardly above the cone and connected to one end of lever 55 fulcrumed at 56 and having connected to its opposite end an operating rod 57. By pulling down on the latter the valve 52 is lifted to open the discharge orifice, and the fine sand and water escapes to the grinding table.

In carrying out the method the sand is deposited in the vessel 10 or other suitable point in the system from the clam shell bucket 16 or other source and sufficient water is supplied, such as through pipe 59 supplying a stream of water to wash the sand out of hopper 18. The water mixed with sand is graded and supplied to the grinding

table and returned therefrom to the grading vessel in a continuous cycle. It is forced upwardly into the grading vessel 10 through the bottom thereof, thereby producing a current of water in the vessel of gradually diminishing velocity upwardly, due to the increasing cross sectional area of said vessel. The particles of sand move in the stream of water until they reach a state of equilibrium, which depends upon the ratio of the horizontal area and wetted surface of the particles of sand to the weight thereof. Inasmuch as the weight varies according to the cube of the dimensions of the particles while the horizontal projection and wetted surface vary merely as the square of the same dimensions, it necessarily follows that the larger and coarser particles drop to a lower point in the upwardly flowing stream of water than do the smaller particles. As a consequence, the sand particles are accurately separated into several grades or sizes. These grades are withdrawn separately and conducted separately to the grinding table by opening the appropriate valve 27, 28 or 29 controlling the several withdrawal pipes from said cone. The sand and water from the grinding table finds its way to the sump 6 whence it is again lifted into the grading vessel by the centrifugal pump 8. On the grinding table more or less of the sand is pulverized to such a degree as to incapacitate it for further service as an abrasive. Such fine particles escape through the overflow 11, while the coarser particles are again regraded and withdrawn. The several grades are withdrawn from the vessel 10 in succession, beginning with the coarsest and continuing through the various grades to the finest. The capability of separately withdrawing the several grades from said vessel enables the change from one grade to another to be made at any time and therefore made as soon as the surface of the glass is in condition to receive a finer grade. As soon as the glass is sufficiently smooth, the supply of material from the cone 10 is discontinued, and the finishing grinding is effected by withdrawing the sand from cone 14, which is effected by opening the discharge opening 50 in its bottom. The material from this cone is taken out from the bottom, thereby taking out the coarsest grades first, the material becoming finer and finer the longer the grinding continues. During all of the grinding with the exception of the final finishing there is a continuous circulation of abrading material and water from the cone 10 to the grinding table, thence to sump 6 and back again into cone 10. The material too fine for further use is washed by the overflow into the sewer and the finest usable grade escapes from the upper stratum in cone 10 to cone 14 for the final finishing operation. To compensate for these with-

drawals from the system fresh material and water are added to the system from time to time. The simultaneous grading and discharge from the grading vessel permits of the use of much smaller and less expensive vessels or cones than with prior forms of apparatus.

This application is in part a division of my application Serial No. 641,484, filed July 31, 1911.

What I claim is:

1. The method of applying abrasives to grinding mechanism, which consists in supplying the material in suspension in a liquid to a vessel and therein separating the same into grades, simultaneously therewith withdrawing the grades from said vessel separately and independently and conducting the same directly to the grinding mechanism, and also simultaneously drawing off from said vessel the finer material for use in the subsequent smoothing and finishing operation.

2. The method of applying abrasives to grinding and smoothing mechanism, which consists in conducting the material mixed with a liquid to a vessel and therein separating the same into grades, and simultaneously therewith withdrawing said grades from said vessel separately and conducting the same to the grinding mechanism.

3. The method of applying abrasives to grinding and smoothing mechanism, which consists in conducting the material mixed with a liquid to a vessel and there separating the same into various grades, withdrawing said several grades separately and conducting each separately directly to the grinding mechanism, and reconducting the used material mixed with a liquid to said grading vessel and regrading the same therein, the grading, regrading and circulation being carried on in an uninterrupted cycle with the material constantly mixed with the liquid.

4. The method of applying abrasives to grinding and smoothing mechanism, which consists in conducting the material mixed with a liquid to a vessel and there separating the same into various grades, and simultaneously therewith withdrawing said grades separately and in any desired sequence from said vessel, and conducting the same directly to the grinding mechanism.

5. The method of applying abrasives to grinding and smoothing mechanism, which consists in conducting the material mixed with a liquid to a vessel and there separating the same into various grades, withdrawing said grades separately and in any desired sequence and conducting the same in said sequence to grinding mechanism, and reconducting the used material mixed with the liquid to the grading vessel and regrading the same therein, said grading, regrading

and circulation being carried on in an uninterrupted cycle with the material constantly mixed with the liquid.

6. The method of applying abrasives to grinding and smoothing mechanism, consisting in conducting the abrasive mixed with water into a tank and therein separating the same into grades, simultaneously eliminating the surplus water and some of the finer material from the upper portion of the tank, and also simultaneously therewith withdrawing coarser material in single separate grades from near the bottom of the tank and conducting the same directly to the grinding mechanism.

7. The method of applying abrasives to grinding and smoothing mechanism, consisting in holding the abrasive constantly mixed with a liquid and when so mixed conducting same into a tank having downwardly converging sides and therein separating the same into grades, simultaneously therewith eliminating the surplus liquid and some of the finer material from the upper portion of the tank, and also simultaneously therewith withdrawing coarser material in single separate grades from near the bottom of the tank and conducting the same directly to the grinding mechanism.

8. The method of applying abrasives to grinding and smoothing mechanism, consisting in conducting the abrasive mixed with water into a tank and therein separating the same into grades, eliminating the surplus water and some of the finer material from the upper portion of the tank, withdrawing coarser material in single separate grades from near the bottom of the tank and conducting the same directly to the grinding mechanism and returning the used material from the grinding mechanism to the tank, all such operations going on simultaneously.

9. The method of applying abrasives to grinding and smoothing mechanism, consisting in introducing the abrasive mixed with water into a tank and therein separating the same into grades, eliminating the surplus water and some of the finer material from the upper portion of the tank, and simultaneously with the admission of ungraded material and the elimination of the surplus water withdrawing material separately and from any desired level in said tank and conducting the same directly to the grinding mechanism.

10. The method of grading and applying abrading material, consisting in separating the same into different grades, conducting the same in a state of suspension to grinding mechanism, and regrading the used material, such grading, regrading and circulation being carried on in an uninterrupted cycle with the material constantly mixed with a liquid.

11. The method of grading and applying abrading material, consisting in separating the same into different grades, conducting the same in a state of suspension to grinding mechanism, and regrading the used material, such grading, regrading and circulation being carried on in an uninterrupted cycle with the material constantly mixed with a liquid, and simultaneously with the regrading adding fresh material to said circulation.

12. The method of grading and applying abrading material, consisting in separating the material into different grades, conducting the graded material mixed with a liquid to grinding mechanism, and regrading all of the used material above a certain size, such grading, regrading and circulation being carried on with the material constantly mixed with a liquid.

13. The method of grading and applying abrading material, consisting in separating the material into different grades, conducting the graded material mixed with a liquid to a grinding machine, withdrawing from such circulation the material below a certain size and the surplus liquid, adding to the circulation fresh material to replace that withdrawn, and regrading all of the used material above a certain size, such grading, regrading and circulation being carried on with the material constantly mixed with a liquid.

14. The method of applying abrasives to grinding and smoothing mechanism, consisting in introducing the abrasive into a tank, maintaining in said tank an upward flow of water, eliminating the surplus water and some of the finer material from the upper portion of the tank, and simultaneously therewith withdrawing the material as required, the various grades being withdrawn independently from different levels, and conducting the same to grinding mechanism.

15. The method of applying abrasives to grinding and smoothing mechanism, consisting in taking the abrasive mixed with water coming from the grinding mechanism and conducting the same into a grading vessel, grading the same therein, and simultaneously with the introduction of the mixture into said vessel withdrawing the material as required, the various grades being withdrawn independently and from different levels therein, and reconducting the same to said grinding mechanism.

16. The method of applying abrasives to grinding and smoothing mechanism, consisting in introducing the material into a vessel with a liquid and therein producing a downward flow or travel of the material relative to the liquid to thereby separate it into several different grades, and simultaneously therewith withdrawing the mate-

70

125

130

rial as required, the several grades being withdrawn from said vessel independently and from different levels therein, and conducting the same to grinding mechanism.

5 17. The method of applying abrasives to 70
grinding mechanism, consisting in projecting
a stream of liquid vertically at a de-
creasing speed in a suitable vessel or tank
and introducing into said vessel the abrad-
ing material, and thereby separating the
10 latter into different grades, eliminating the
surplus liquid and some of the finer mate-
rial from the upper portion of the tank,
and simultaneously therewith withdrawing
15 the material as required, the several grades
being withdrawn independently and from
different levels therein, and conducting the
same to grinding mechanism.

18. The method of applying abrasives to 80
20 grinding mechanism consisting in conduct-
ing the abrasive mixed with a liquid into a
vessel and producing in said vessel a down-
ward flow or travel of the material relative
25 to the liquid and thereby separating the
material into grades, withdrawing the finer
material from the upper stratum of said
vessel to a second vessel, simultaneously
30 with the introduction of the material into
said first named vessel separately withdraw-
35 ing the several grades therefrom as required
and conducting the same to the grinding
mechanism, producing an upward flow of
liquid relative to the material in the second
40 named vessel and thereby grading the mate-
rial therein, and finally withdrawing the
material from said second named vessel.

19. The method of applying abrasives to 90
grinding mechanism, consisting in project-
ing upwardly into a vessel a stream of a liq-
uid mixed with abrasives thereby producing
45 a decreasing flow upwardly and separating
said material into grades, withdrawing the
coarser grades from said vessel independ-
ently and from different levels thereof and
conducting the same to grinding mecha-
50 nism, withdrawing the finer grades from
the upper stratum of said vessel to a second
vessel and therein producing an upward
flow of a liquid relative to the material to
55 thereby grade the material in said second
vessel, and finally withdrawing the graded
material from said second vessel and con-
ducting the same to the grinding mecha-
nism.

55 20. The method of applying abrasives to 100
grinding mechanism, consisting in project-
ing upwardly into a vessel provided with
converging walls a stream of a liquid mixed
60 with abrasives thereby producing a decreas-
ing flow upwardly and separating said mate-
rial into grades, withdrawing the coarser
grades from said vessel independently and
from different levels therein and conducting
65 the same to grinding mechanism, withdraw-
ing the finer grades from the upper stratum

of said vessel to a second vessel and therein
producing an upward flow of a liquid relative
75 to the material to thereby grade the
material in said second vessel, and finally
withdrawing the graded material from said
second vessel and conducting the same to the
grinding mechanism, returning the material
80 from said grinding mechanism to the first
named vessel and regrading the same
therein.

21. The method of applying abrasives to 85
grinding mechanism, which consists in con-
ducting the abrasive mixed with a liquid
first to the grinding mechanism and then to
a grading vessel or tank, and there sepa-
90 rating the coarse material and conducting
the same back to the grinding mechanism,
while at the same time holding some of the
finer grades still mixed with the liquid in
the grading vessel or tank.

22. The method of applying abrasives to 95
grinding mechanism, which consists in con-
ducting the abrasive mixed with a liquid
first to the grinding mechanism and then to
a grading vessel or tank, and there sepa-
100 rating the coarse material and conducting
the same back to the grinding mechanism,
while at the same time holding some of the
finer grades still mixed with the liquid in
the grading vessel or tank, and subsequently
conducting some of the finer grades to the
105 grinding mechanism.

23. The method of applying abrasives to 110
grinding mechanism, which consists in con-
ducting the abrasive mixed with a liquid
first to the grinding mechanism and then
to a grading vessel or tank, and there sepa-
115 rating the coarse material and conducting
the same back to the grinding mechanism,
while at the same time holding the finer
grades still mixed with the liquid in the
grading vessel or tank, separating the finer
120 material into grades, and subsequently con-
ducting the finer grades in any desired
sequence to the grinding mechanism.

24. The method of applying abrasives to 125
grinding mechanism, which consists in con-
ducting the abrasive mixed with a liquid
first to the grinding mechanism and then
to a grading vessel or tank, and there sepa-
130 rating the coarse material and eliminating
the surplus liquid and the material too fine
for use, conducting the coarse material back
to the grinding mechanism, and simultane-
ously holding some of the finer grades in
suspension in the liquid in the grading ves-
sel or tank.

25. The method of applying abrasives to 135
grinding mechanism, which consists in con-
ducting the abrasive mixed with a liquid
first to the grinding mechanism and then
to a grading vessel or tank, and there sepa-
rating the coarse material, and eliminating
the surplus liquid and the material too fine
for use, conducting the coarse material back

to the grinding mechanism, simultaneously holding some of the finer grades in suspension in the liquid in the grading vessel or tank, and subsequently conducting some of the finer grades to the grinding mechanism.

26. The method of applying abrasives to grinding mechanism, which consists in conducting the abrasive mixed with the liquid to the grinding mechanism, collecting the drainage therefrom and conducting the same to and introducing the same into a primary grading vessel containing a relatively deep body of the abrasive mixed with the liquid and there subjecting the particles of the abrasive to an upward movement of the liquid relative to the movement of the abrasive, whereby the abrasive is stratified in the liquid, withdrawing the coarse material from near the bottom of the vessel and conducting the same to the grinding mechanism, withdrawing the fine material from near the upper portion of the primary grader to a secondary grader while at the same time holding the intermediate grades still mixed with the liquid in the primary grader, and after the rough grinding operation is finished withdrawing the desired finer grades from the primary grading vessel to the grinding mechanism.

27. The method of applying abrasives to grinding mechanism, which consists in conducting the abrasive mixed with the liquid to the grinding mechanism, collecting the drainage therefrom and conducting the same to and introducing the same into a primary grading vessel containing a relatively deep body of the abrasive mixed with the liquid and there subjecting the particles of the abrasive to an upward movement of the liquid relative to the movement of the abrasive, whereby the abrasive is stratified in the liquid, withdrawing the coarse material from near the bottom of the vessel and conducting the same to the grinding mechanism, withdrawing the fine material from near the upper portion of the primary grader to a secondary grader while at the same time holding the intermediate grades still mixed with the liquid in the primary grader, after the rough grinding operation is finished withdrawing the desired finer grades from the primary grading vessel to the grinding mechanism, and subsequently conducting fine material from the secondary grader to the grinding mechanism.

28. The method of applying abrasives to grinding mechanism, which consists in conducting the abrasive mixed with a liquid first to the grinding mechanism and then to a grading vessel or tank containing a relatively large, deep body of the abrasive mixed with the liquid, and there separating the same into a series of grades, and while grading the abrasive material conducting the coarse material from said vessel or tank

directly to the grinding mechanism and the fine material to a secondary grading vessel, and maintaining the intermediate grades suspended in the primary grading vessel.

29. The method of applying abrasives to 70 grinding mechanism, which consists in conducting the abrasive mixed with the liquid to the grinding mechanism, collecting the drainage therefrom and conducting the same to and introducing the same into a primary grading vessel or tank below the surface of the liquid therein, there separating the same into a series of grades, conducting the coarse material from said vessel or tank directly to the grinding mechanism, withdrawing the fine material from the primary grading vessel at a level above the inlet thereto and conducting the same to a secondary grading vessel, and after the rough grinding operation is finished conducting some of the finer material from the secondary grading vessel 85 or tank to the grinding mechanism.

30. The method of applying abrasives to 90 grinding mechanism, which consists in conducting the abrasive mixed with the liquid first to the grinding mechanism and then to a primary grading vessel or tank and introducing the same thereinto below the surface of the liquid therein, separating the abrasive into a series of grades and simultaneously conducting the coarse material to the grinding mechanism, withdrawing the fine material from the primary grading vessel or tank at a level above the inlet thereto, and maintaining the intermediate grades suspended in the primary grading vessel or tank.

31. The method of applying abrasives to 95 grinding mechanism, which consists in conducting the abrasive mixed with the liquid to the grinding mechanism, collecting the drainage therefrom and conducting the same to and introducing the same below the surface of a large, deep body of the material mixed with the liquid, there separating the 100 material into grades, and simultaneously withdrawing the coarse material and conducting the same directly to the grinding mechanism.

32. The method of applying abrasives to 115 grinding mechanism, which consists in conducting the abrasive mixed with the liquid to the grinding mechanism, collecting the drainage therefrom and conducting the same to and introducing the same below the surface of a large, deep body of the material mixed with the liquid, there separating the material into grades, withdrawing the coarse material and conducting the same directly to the grinding mechanism, and withdrawing 120 the fine material from the upper portion of the body of material mixed with the liquid and conducting the same to a secondary grading vessel.

33. The method of applying abrasives to 130

- grinding mechanism, which consists in conducting the abrasive mixed with the liquid to the grinding mechanism, collecting the drainage therefrom and conducting the same to and introducing the same below the surface of a large, deep body of the material mixed with the liquid in a primary grading vessel or tank, eliminating the surplus liquid and the material too fine for use from said grading vessel or tank and separating the rest of the material into a series of grades, withdrawing the fine material from said grading vessel at a level above the inlet thereto and introducing the same into a secondary grading vessel or tank, and withdrawing the coarse material from near the bottom of the primary grading vessel or tank and conducting the same directly to the grinding mechanism.
34. The method of applying abrasives to grinding mechanism, which consists in conducting the abrasive mixed with the liquid to the grinding mechanism, collecting the drainage therefrom and conducting the same to and introducing the same below the surface of a large, deep body of the material mixed with the liquid in a primary grading vessel or tank, eliminating the surplus liquid and the material too fine for use from said grading vessel or tank and separating the rest of the material into a series of grades, withdrawing the fine material from said grading vessel at a level above the inlet thereto and introducing the same into a secondary grading vessel or tank, withdrawing the coarse material from near the bottom of the primary grading vessel or tank and conducting the same directly to the grinding mechanism, and after the rough grinding operation is finished conducting the fine material from the secondary grading vessel or tank to the grinding mechanism.
35. The method of applying abrasive to

grinding mechanism, which consists in conducting the abrasive mixed with a liquid to the grinding mechanism, collecting the drainage therefrom and conducting the same to and introducing the same into a vessel and there increasing the proportion of the abrasive material relative to the liquid and separating the material into grades, and reconducting the condensed grades from said vessel to the grinding mechanism.

36. The method of applying abrasives to grinding mechanism, which consists in conducting the abrasive mixed with a liquid to the grinding mechanism, collecting the drainage therefrom and conducting the same to and introducing the same into a vessel or tank, withdrawing the coarser material and reconducting the same to the grinding mechanism, and simultaneously increasing the proportion of the finer material relative to the liquid and maintaining the condensed mixture in suspension in the liquid in said vessel or tank.

37. The method of applying abrasives to grinding mechanism, which consists in conducting the abrasive mixed with a liquid to the grinding mechanism, collecting the drainage therefrom and conducting the same to and introducing the same into a vessel or tank, withdrawing the coarser material and reconducting the same to the grinding mechanism, simultaneously increasing the proportion of the finer material relative to the liquid and maintaining the condensed mixture in suspension in the liquid in said vessel or tank, and subsequently withdrawing the condensed finer grades and conducting the same to the grinding mechanism.

In testimony whereof, I have hereunto set my hand.

HALBERT K. HITCHCOCK.

Witnesses:

Wm. P. LARKIN,

WILLIAM B. WHARTON.
